FIG. 4

Des. 200,984

PAGE 5

F/G. 6

FIGURE 1 is a front perspective view of a microfilmer showing my new design;

FIGURE 2 is an enlarged front elevational view thereof; FIGURE 3 is a left-side elevational view thereof; FIGURE 4 is a right-side elevational view thereof; FIGURE 5 is a top plan view thereof; and FIGURE 6 is a rear elevational view thereof.

The bottom (not shown) of the microfilmer is conventional and without ornamentation.

I claim:

The ornamental design for a microfilmer, as shown and described.
